UNITED STATES PATENT OFFICE

2,612,347

POR TABLE DRILLING UNIT

Sisti Siracusa, Santa Fe Springs, Calif.

Application April 5, 1949, Serial No. 85,545

2 Claims. (Cl. 255—19)

2 Claims. (Cl. 255—19.)

1

This invention relates to a portable drilling unit, and particularly, that portion of the drilling unit which is known as a powered swivel.

My invention relates to a drilling unit which is applicable to all types of light rotary operations on a well.

An object of my invention is to provide a portable drilling unit, which eliminates the necessity of moving large and heavy kellys, rotary tables, and other heavy equipment into a derrick.

My invention is applicable for all light rotary work, and particularly, the work which requires a short time, thus eliminating the inefficiency and

My invention is applicable to casing, drill pipe and tubing cutting for drilling out cement, for backing off sucker rods and tubing, for drilling out obstructions in casing and tubing, for milling operations, for scraping liners etc.

Another object of my invention is to provide a novel portable drilling unit which is compact and simple in construction, which can be readily moved into position in a derrick and supported therein, a unit being provided with means to prevent its rotation under high torque stresses.

Another object of my invention is to provide a drilling unit of the character stated, which can be rotated in either direction as desired by the operator.

A feature of my invention is the inclusion of a fluid motor to drive the unit, thus eliminating the possibility of fire and also enabling the unit to be driven from a remote source.

Other objects, advantages and features of invention may appear from the accompanying drawing, the subjoined detailed description and the appended claims.

In the drawing

Figure 1 is a side elevation of my portable drilling unit.

Figure 2 is a fragmentary side elevation as viewed from the side opposite that shown in Figure 1, and with the cover of the gear case removed.

Figure 3 is a sectional view taken on line 3—3 45 of Figure 4.

Figure 4 is a longitudinal sectional view of my portable drilling unit.

Referring more particularly to the drawing, the numeral 1 indicates an outer housing or case, which is held stationary as far as rotation is concerned, by means of a torque bar 2, which fits in a sleeve 3, formed on the case 1. A rein 4 extends from the bar 2 to a leg of the derrick, thus holding the case 1 against rotation, particularly when

there is a considerable strain or torque on the drilling unit.

A fluid motor 5 is attached to the case 1, and this motor drives the pinion 6, the pinion in turn meshing with and rotating the gear 1, which is attached to the shaft 8. The gears 6 and 7 are positioned in a gear case 9, which is fixedly mounted on, or may be, an integral part of the housing 1. A worm 10 is mounted on the shaft 8, and this worm meshes with a worm wheel 11, which is mounted within the housing 1 in a substantially horizontal plane. The worm wheel 11 is fixedly attached to, or may be, integral with a bushing 12, and this bushing is supported on bearings 13 and 14 within the housing 1. The fluid motor 5 is provided with alternative intake pipes 15 and 16, one driving the motor in one direction and the other in the opposite direction. A return or relief pipe 17 also extends from the motor.

20 An elevator sub 18 screws into the top of the housing 1 or is otherwise fixedly attached thereto. The elevator sub receives the elevators (not shown), which support instruments of this type. A ring 19 is used as a pick up eye to support the drilling unit while it is being moved into operating position in a derrick, that is, a hook can be inserted in the eye 19, thus supporting the entire unit to swing it into the derrick and also holding it while the elevators are being attached. A second eye 20 is fixedly attached to the housing 1 and this eye extends horizontally so that the drilling unit can be pulled horizontally by means of block and tackle, or other means when it is desired to center the drilling unit at a particular point.

35 A drive sub 21 is detachably secured to the lower end of the bushing 12 by means of the spindle cap or nut 22. The spindle nut screws on to the lower end of the bushing and shoulders on the sub 21, thus holding the sub to rotate with the bushing, which is driven by the gear 11, as previously described. The drive sub 21 can be replaced by removing the nut 22 when necessary.

Operation

In operation, the drilling unit is supported in a derrick from an elevator, in the usual and well known manner. The power unit which supplies fluid under pressure is placed some distance from the derrick. The fluid under pressure can be directed into either of the pipes 15 or 16, as desired by the operator. The fluid motor 5 is thus caused to rotate and the gears 6, 7, 10 and 11 are thus rotated, which rotates the bushing 12 and the drive sub 21. The drive sub 21 screws into the

pipe tubing or the like, which extends downwardly into the well, all of which is usual and well known in the art. When the particular work in the derrick is completed, the drilling unit can be quickly swung out of the derrick and removed to another location.

Having described my invention, I claim:

1. A portable drilling unit comprising a housing, a fluid motor mounted on said housing, a worm wheel journaled in said housing, a worm meshing with said worm wheel, gear means extending from said motor to said worm whereby the worm is rotated, a bushing depending from the worm wheel a shoulder on the bushing above the worm wheel, a second shoulder on the bushing below the worm wheel, bearings in said housing engaging the shoulders on the bushing, a drive sub attached to the bushing and depending therefrom, a nut threaded on to said bushing and shouldering on the sub whereby the sub is detachably secured to the bushing, and an elevator sub rising from said housing and threaded into said housing.

2. A portable drilling unit comprising a housing, a fluid motor, means fixedly attaching the fluid motor on the outside of said housing, a worm wheel journaled in said housing, a worm meshing with said worm wheel, gear means extending from said motor to said worm whereby

the worm is rotated, a bushing depending from the worm wheel, a shoulder on the bushing above the worm wheel, a second shoulder on the bushing below the worm wheel, bearings in said housing engaging the shoulders on the bushing, a drive sub fitted in said bushing and depending therefrom, a nut threaded on to said bushing and shouldering on the sub whereby the sub is detachably secured to the bushing, an elevator threaded into the top of the housing, and a ring mounted on the upper end of the elevator sub.

SISTI SIRACUSA.

5 10 15 20 25

the worm is rotated, a bushing depending from the worm wheel, a shoulder on the bushing above the worm wheel, a second shoulder on the bushing below the worm wheel, bearings in said housing engaging the shoulders on the bushing, a drive sub fitted in said bushing and depending therefrom, a nut threaded on to said bushing and shouldering on the sub whereby the sub is detachably secured to the bushing, an elevator threaded into the top of the housing, and a ring mounted on the upper end of the elevator sub.
